UNITED STATES PATENT OFFICE

CLARA AMELIA PENROSE, OF LONDON, ENGLAND, ASSIGNOR OF ONE-HALF TO PHILIP OWEN PENROSE, OF LONDON, ENGLAND

CONVERTIBLE FURNITURE

Application filed March 2, 1931, Serial No. 519,557, and in Great Britain March 3, 1930.

This invention relates to convertible furniture and has among its objects to provide an improved device of this character having numerous applications and uses and which, if desired, may be readily dismantled and packed into a small and compact form for transport.

According to the present invention, the improved device comprises a framework adapted to provide a rigid rectangular structure for the support of one or more movable leaf members forming a table, dinner wagon or the like, and at one or each end of the framework a folding seat member hinged or otherwise mounted to form, when opened out or extended, an elevated seat for the support of a child up to the top of the device, such seat member being adapted, when folded or collapsed, to fit within or to lie against the respective end frame or member of the supporting framework. The leaf member or members may be slidably mounted and the supporting structure may be adapted for the location or support of such member or members in an alternative position or positions to provide a child's cot, a settee, an occasional or card table, a school desk, a bed-table or a music stool as desired. A collapsible rubber bath may be provided to fit into the device when it is adapted for use as a cot, and a book or music rest may be provided comprising a supporting rod which may be fitted into a suitable hole or socket at one or more positions in the structure and which may also serve for the support of a canopy when the device is used as a cot. Furthermore, one or more detachable trays adapted to be supported at the end or ends of the structure, for instance by the seat-supporting members, may be provided.

The book rest and the tray or trays normally may be located when out of use within the end frames of the structure. Furthermore, one of the leaf or shelf members may be provided with means on its underside for the support of air cushions or the like when out of use. Preferably, the supporting framework is constructed so that it is collapsible in such manner that the whole device may be packed into a compact form for transport.

For this purpose, the structure may comprise two end frames adapted to be connected together by means of readily detachable struts or the like. The supporting framework preferably is fitted with castor wheels or the like.

The invention is hereinafter described by way of example with reference to the accompanying diagrammatic drawings, in which:

Figure 1 is a side elevation of an article of convertible furniture according to the invention, showing the parts in position to provide a table or dinner wagon and with one child's seat open or extended;

Figure 2 is an end elevation corresponding to Figure 1;

Figure 3 is a plan view corresponding to Figure 1;

Figure 4 is a detail sectional view illustrating a preferred form of catch for locating the slideable leaf members;

Figure 5 is a line diagram illustrating in perspective the arrangement of the parts for use as an occasional or card table;

Figure 6 is a similar view showing the device converted for use as a cot;

Figure 7 is a similar view showing the device converted for use as a settee; and

Figure 8 is a similar view showing the device converted for use as a music stool.

In carrying the invention into effect according to one construction, the improved device comprises a supporting framework consisting of two end frames each of which is formed to provide a pair of vertical members 1 connected at the top and also adjacent the lower end by horizontal cross-pieces 2, 3 respectively. The end frames are spaced apart adjacent the lower end by means of struts 4 which may engage the end frames by means of dowels and may be clamped thereto by means of any suitable form of clamping device 5. The end frames may be braced to the struts 4 by means of stay rods 6 pivotally connected to the struts 4 and at their upper ends engaging with slotted plates 7 or the like fixed to the vertical members 1, thumb nuts 6a or the like being provided for tightening the stay rods 6. At one side the end frames are connected adjacent the top by means of a

strut 8 which may be fixed to the end frames by means of removable pins 8a or other suitable means. At a substantially middle position in the height of the structure, the end frames are formed at their inner sides with ledges 9 for the support of a leaf 10 which is prevented from sliding out of position by the vertical flanges 1a on the members 1.

- 10 Each end frame is fitted at the inner side with spaced horizontal ledges 1b, 1c, 1d, the upper ledges 1b serving for the support of the top leaf member 11, and the ledges 1c, 1d for the alternative support of an auxiliary leaf member 12, the leaf members 11 and 12 being slidable into position through slots or openings 1e, 1f, 1g respectively in the flange 1a. The flanges 1a, together with spaced parallel guides 1h serve to provide vertical channels 1m for the alternative reception of the leaf 11 or the leaf 12. It will be seen that the upper ledge 1b is on a level with the lower edge of the respective slot 1e and in order to prevent the leaf 11 from sliding out sideways, spring catches 13 are provided, such catches, as shown more especially in Figure 4, consisting of a plunger 13a adapted to engage in a hole 11a in the edge of the leaf 11 under the action of a spring 13b, the outer end of the plunger being pivotally connected to a cam lever or member 13c at a point so located in relation to the edges of the member that the plunger 13a may be readily held in the completely withdrawn position or in a half withdrawn position in which the rounded end of the plunger 13a acts as a ball catch. The edges of the leaf members preferably are protected by sheet metal channel members such as 11b (Figure 4). Additional slots 1n are formed in the flange 1a at the side opposite to the strut 8 to afford an alternative support for the respective side of the auxiliary leaf member 12 when the device is to be used as a settee, in which case the other side of the leaf 12 rests upon the leaf 10.
- 15 20 25 30 35 40 45 50 55 60 65
- The top leaf 11 is formed on its underside with a guiding member 11c which in conjunction with one end frame member may serve to locate the auxiliary leaf member 12 so that it extends lengthwise at one side of the structure to form a bed-table, the leaf member 12 in this position being supported by the strut 8. The leaf 10 may be fitted with eyelets or the like at its underside for the suspension of a frame 14 which serves to carry air cushions and the like for use with the device, the suspending-cords 14a or the like being connected to a common ring 14b and passing between a pair of pulleys or other guiding members 14c so that by pulling the ring outwardly and anchoring it to a hook or projection 14d, the frame 14 may be drawn close up beneath the leaf 10. As an additional means of stiffening the framework, the leaf 10 may be clamped to the end frames by means of any suitable clamping devices

5a, for instance having a link for engaging a hook on one part and co-operating with a cam lever device on the other part.

Each end frame is provided with cross-struts 2a, 2b and the central opening 2e between the struts may serve for the reception of a tray 15 at one end and a book or music rest 16 at the other end, such rest 16 having a supporting rod 16a and the tray 15 and rest 16 being held in position by means of fastenings, such as 2d.

At each end of the frame two hingedly mounted brackets 17 are provided, which brackets 17 may serve as handles for lifting the device as a whole, but mainly serving, when opened out, for the support of a seat 18 having a hinged back 19 connected to the seat by means of a hinged strut 20.

The seat is pivoted to brackets fixed to the members 1 and the parts are so arranged that the back 19 may be folded down upon the seat 18 and the parts then folded upwardly into the position shown at the right-hand end of Figure 1, in which position they are held by the engagement of a ball catch or the like provided at the underside of the projecting part 1p on the cross-strut 2. In order to prevent any possibility of the seat being disengaged from the supporting member 17 and at the same time to afford additional protection for the child in the seat, two side gate members 21, 22 are provided, such members 21, 22 being hinged vertically to the end frames in such manner that when out of use they fold into the space between the upper cross-strut 2 and the cross-strut 2a. The supporting members 17 engage with a recessed cross-member 18a fixed to the underside of the seat 18, and it is to be noted that the gate members 21, 22 cannot be opened unless the seat is correctly engaged with the supporting members 17. The tray 15 referred to is fitted with a flanged metal fitting 15a adapted to engage slidably with a metal plate 17a upon the end of one or the other of the brackets 17, while the rod 16a of the book or music rest may be engaged with one of the brackets 17 at the front side of the structure or fitted into a hole 2e in one of the upper cross-struts 2, in which position it serves as a music rest or, if the rod 16a is used alone, for the support of a canopy in the case where the device is used as a cot. The vertical members 1 of the framework preferably are fitted at the lower end with castor wheels 23.

As illustrated diagrammatically in Figure 5, the device may be modified for use as an occasional table by disengaging the upper catches 13 and inserting the leaf 12 in the same plane as the leaf 11, the catches 13 being engaged with suitably arranged holes in the edges of the leaves 11 and 12 so as to hold them with their meeting edges at the middle of the structure. With this arrangement, the seats may be partly opened out so that

the backs 19 of the seats form auxiliary tables for the support of cups or the like.

As shown in Figure 6, the device may be modified for use as a cot by removing the leaves 11 and 12 from the position shown in Figure 1 and inserting them in the vertical guides at the sides of the end frames, in which positions they may be held by the catches 13 or other suitable means. In this arrangement, the rods 16a may be inserted in the hole 2e to support a canopy, while the brackets 17 may be opened out to provide handles for lifting the cot from place to place.

As shown in Figure 7, the device may be used as a settee by inserting the top leaf 11 so that it is at an inclination, in which position it may be located by suitably arranged stops or guides at the inner sides of the end frames, and by inserting the auxiliary leaf member 12 into the slots 1n so that its rear edge rests upon the leaf 10 and thus forms an inclined seat. In this arrangement, the book rest 16 may have its supporting rod 16a inserted in a hole in one of the brackets 17, and the tray 15 may be mounted upon one of the brackets 17.

As shown in Figure 8, the top leaf 11 may be inserted into the vertical guides at the rear side of the structure, in which position it is held by the respective catches 13, and the auxiliary leaf 12 is inserted into the slots 1g and rests upon the ledges 1c thus providing a stool of suitable height for use at the piano. In this arrangement, the music rest 16 may have its rod 16a inserted in the hole 2e in the respective cross-strut 2 to provide a rest of suitable height for use, for instance, by a violinist.

The device also may be adapted for use as a school desk, in which case the leaf 11 is displaced towards the rear, for instance, into the position shown in Figure 5, while the leaf 12 is inserted into the slots 1g so that its rear edge is approximately below the front edge of the leaf 11, thus forming a seat for children, using the leaf 11 as a desk and resting their feet upon the leaf 10.

It will be understood that the invention is not limited to the details of construction hereinbefore described. Thus, the supporting framework may be constructed in any other suitable manner, while the means for supporting the flap members and seat members in the various positions may be modified in various ways without departing from the scope of the invention. For instance, in place of the brackets 17 and hinged struts 20, slotted links, chains or other equivalent means may be provided for sustaining the seats. Furthermore, if desired, one or more drawers may be provided in any suitable position for instance, beneath the lower shelf member.

The cushions may be held in position by press-button fasteners or the like, while the

framework, although preferably made of wood, if desired, may be constructed in metal, or other suitable material.

If air cushions are employed, a suitable inflating device may be fixed to one of the end frames, and if desired, may be adapted to be operated by oscillating one of the hinged stretcher handles connected in any suitable manner to the piston of the inflator.

What I claim is:—

1. An article of furniture comprising a supporting frame, a seat member hinged at one edge to the frame to swing upward against the frame or extend horizontally therefrom, a back rest hinged to the free edge of the seat member to fold over thereonto or extend upwardly therefrom, foldable braces pivoted to the seat member and to the back rest, side members hinged to the frame above the seat member to extend in vertical planes over the seat member against the inner sides of the braces, and brackets hinged to the frame below the seat member to extend out under the seat member and constitute supports therefor and handles for moving the frame.

2. An article of furniture comprising a supporting frame, a seat member hinged at one edge to the frame to swing upward against the frame or extend horizontally therefrom, a back rest hinged to the free edge of the seat member to fold over thereonto or extend upwardly therefrom, foldable braces pivoted to the seat member and to the back rest, side members hinged to the frame above the seat member to extend out in vertical planes over the seat member against the inner sides of the braces, brackets hinged to the frame below the seat member to extend out under the seat member and constitute supports for said member and handles for moving the frame, and a cross member on the under side of the seat member engageable with said brackets.

In testimony whereof I have hereunto signed my name.

CLARA AMELIA PENROSE.
